UNITED STATES PATENT OFFICE.

FRANK COLONNA, OF BROOKLYN, NEW YORK.

AUTOMATIC THERMOSTATIC GAS CUT-OFF.

Application filed December 5, 1923. Serial No. 678,564.

To all whom it may concern:

Be it known that I, FRANK COLONNA, a citizen of the United States, and a resident of the borough of Brooklyn, county of 5 Kings, city and State of New York, have invented an Improvement in Automatic Thermostatic Gas Cut-Offs, of which the following is a specification.

My present invention relates to automatic 10 cut-offs for combustible fluids, such as illuminating and heating gas, and more particularly to an automatic cut-off, actuated thermostatically. This invention finds particular use in connection with burners in 15 furnaces, ranges and radiators, and in connection with illuminating burners and the like.

It is an object of the present invention to provide an improved fluid cut-off which 20 shall positively cut off all the fluid supply to a burner or burners consuming such fluid the moment its quantity or volume passing to the burner or burners drops to such a degree insufficient to support a flame.

It is another object of the invention to 25 provide a simple but positive actuating device which automatically shuts off the supply of a combustible fluid to a burner burning such a fluid whenever the pressure of the fluid in the supply pipe reaches a point insufficient to support combustion.

It is still another object of the invention to 30 provide a device which shall automatically cut off the combustible fluid supply to a burner or burners whenever such burner or burners have, for any reason, their flame or flames extinguished.

It is a further object of the invention to 35 provide an inexpensive and durable device, of the character stated, which shall prevent the passage of combustible fluid to an extinguished burner, and which shall have also shut said supply of combustible fluid at a predetermined time without the aid of 40 human attendance.

Other objects of the invention, together 45 with its advantages and distinguishing features, shall appear in the accompanying specification which is descriptive of one embodiment of the invention, as illustrated in

the accompanying drawings forming a part of said specification, it being understood that the said drawings are only illustrative of one embodiment of the invention to which I do not limit myself, since the same could 55 be easily varied and changed without in the least departing from the spirit thereof.

Referring to the said illustrative embodiment of the invention in the drawing:

Figure 1 is a front elevation of said illustrative embodiment of the invention shown connected with the fluid supply pipe of a radiator and of an illuminating burner;

Fig. 2 is a rear view of the upper portion of the device showing its connection 65 with a clock mechanism for enabling a shut off of the fluid supply to the illuminating or heating appliances or both at a set or prefixed time;

Fig. 3 shows the inner view of the device, 70 with the clock removed, illustrating the preferable form of the operating mechanism of the device together with the cooperating clock operated means;

Fig. 4 is a longitudinal sectional view 75 taken on a line 4—4 in Fig. 3 and showing the operated mechanism sidewise;

Fig. 5 is a view similar to that in Fig. 3 but showing a modified form of the invention; and

Fig. 6 is a fragmentary view of the device taken on line 6—6 in Fig. 3 in the direction of the arrows showing certain clock actuated means in co-action with the mechanism in the device.

Before describing the invention in accordance with the illustrated example, it is thought desirable to briefly state the field to which it pertains and what difficulties and troubles it shall eliminate therein. The danger of death and fire from illuminating and heating fluids, such as what is commonly known as gas, is an appalling nightmare in the life of those persons inhabiting dwellings furnished with gas appliances. Although many devices, improvements, rules and regulations have been devised and suggested to minimize such danger, the rate of death and property damage from free illuminating gas in the air is as heavy as 100

ever. Most of the time when the air is charged with gas in quantities to cause asphyxiation or fires or both, the source of its escape is invariably traced to open jets or burners. These jets or burners discharge gas into the air whenever their flames have been extinguished by causes other than a shut-off by an attendant. The causes of flame extinguishments usually arise from 10 decrease of gas pressure in the mains, temporary shut-offs at the gas plants, poor mixture of air and gas to the burner, or gust of wind against the flame.

The above enumerated causes and others 15 of like nature, not mentioned, render the use of illuminating gas in the home so hazardous and risky that its use, essential as it is in the home, is restricted only to indispensable house appliances, to the discomfort of the 20 public at large and to the financial loss of the gas industry. But the discomfort arising from the restriction of use of gas on the part of the public and the financial loss for the same reasons on the part of the gas 25 industry can be remedied by a device such as that forming the subject matter of this invention, by means of which, the gas supply to the household appliances provided with such a device may be entirely cut off the 30 moment the flames of the burners of the appliances become extinguished or are about to become extinguished.

In Fig. 1 to the radiator 10, which may be of any kind or shape, a fluid supply pipe 11 is connected to which may be connected a second pipe 12 to supply illuminating fluid to the burner 13. The pipe 12 of course may be dispensed with or it may be provided with a device of its own to control its own 40 flow of fluid. This pipe is shown connected to the pipe 11 only to show the possibility of controlling the burners 14 of the radiator and the illuminating burner 13 from the same device. The device itself is shown by the numeral 15 which may be preferably inclosed in a casing or box 17 having its front part 18 removable so as to get to the mechanism which the box contains. This box 17 may accommodate the fitting 20 housing the 45 valve 21 to open and close the discharge of fluid to the pipe 11 from the main supply 22. Both the pipe 11 and the main supply 22 are connectible to the fitting 20 through any approved means such as the nuts 23. Thus 50 when these two pipes are connected to the fitting 20 which, being secured to the box 17 by means of bolts and nuts 25, the main 22 and the pipe 11 sustain the box and the mechanism carried therein.

The box has secured thereto, in any approved manner, a shell 28 perforated as at 55 29 at its upper side. This shell constitutes an air chamber into which rises the air heated by a pilot burner 30 fed from the pipe 11. When the pilot burner 30

is burning, the air heated by its flame rises upwardly into the chamber and escapes through the perforations 29. The burner 30 may be eliminated, if convenient, and in its stead a conduit 35 may be employed which is connected to and extends from the radiator 10 with one end directed upwardly to discharge into the shell 28. This conduit 35 conducts the heated air from the radiator 10 into the chamber formed by the shell 28 and in this manner a similar effect is had therein as if the burner 30 was burning. Of course the conduit 35 may be provided with a valve (not shown) for shutting off the flow of air therethrough. This conduit may be used in association with the burner 30 so that the flow of heated air through the chamber may be supplied by the burner 30 and the conduit 35, jointly or severally.

To the box 17 is secured the mechanism indicated generally by the number 38 which is secured to the box through any suitable means such as the rivets or screws 39. This mechanism may suitably comprise a train of gears 40 having principally the master gear 41 and the controlling gear 42, the master gear 41 being provided with a spring 43 against which it is wound when the valve 21 is opened, the controlling gear 42 acting as a restraining member for the gear 41 which is prevented from rotating under the influence of the spring by the gear 42, the two gears being intermeshed through intermediate gears 45 and 46. The last-mentioned gears 45 and 46, may be eliminated if desired and the gear 42 may be either meshed directly with the master gear 41 or also be eliminated with the others and the master gear 41, by a slight modification, may be made to act as the master gear and also the controlling gear. All of these gears are suitably held assembled in a frame 49 to which may be pivoted, as at 50, a pawl 51 formed with tooth 53 at one end and an off-set portion 54 at the other which may carry the balancing means 55 consisting of nuts or like elements which, when advanced or retracted to and from the end of the off-set portion, will tend to balance the pawl 51 on its pivot. This pawl may be varied in size and shape without affecting its purpose and scope. The tooth 53 of the pawl 51 may engage with the teeth 60 of the controlling gear 42, and thus when the two engage with each other, the controlling gear 42 is prevented from rotating under the influence of the spring 43. When the tooth 53 is disengaged from the teeth 60 and the gear 41 is wound against the gears 40, all will rotate until the pressure of the spring 43 has been exhausted.

To the axle of the master gear 41 may be mounted a crank 65 which is connected to the crank 66, secured to the valve 21, by

means of the pitman or link 67. Through these cranks and link the movement of the gear mechanism 40 is transmitted to the valve 21 and thus the opening and closing of the valve 21 may be effected directly by the rotation of the gears 40. The cranks 65 and 66 of the link 67 are not absolutely necessary for in their place a train of gears 69 may be employed, as shown in Fig. 5.

10 Mounted on the frame 49 is a bracket 71 on which is pivoted the thermostatically operated device 72 which carries at one end a floater or an air buffer plate 73 and at the other a pawl engaging member 74. This 15 thermostatically operated member 72 preferably has a tube 75 intermediate the floater 73 and the pawl engaging member 74, in which are accommodated one or more balls 76 free to travel from one end of the 20 tube to the other and meant to expedite the oscillating movement of the thermostatically operated device 72; for as soon as the tube 75 swings in any position, slightly off the horizontal plane, the balls 25 begin to travel in the direction of that end which is below the horizontal plane and quicken the movement of that end downwardly. It will be noted that the distance between the end of the tube carrying the 30 pawl engaging member 74 and the center of the bracket 71 is shorter than the distance between the center of the bracket and the other end of the tube and when the balls 35 76 occupy the position shown in Fig. 3, that is the position near the inner end of the tube, unless there is radiating air passing through the chamber formed by the shell 28, the tube 72 together with the floater 73 will tend to move clockwise, for the weight of these balls and that of the 40 part of the device extending between the bracket and the element 74 are not sufficient to counterbalance the weight between the bracket and the other end of the tube. The shank 79 of the pawl engaging element 74 may be conveniently threaded so as to carry the nuts 80 which are meant to be moved in one direction or the other along the shank to properly adjust the balance of the thermostatically operated elements 72.

In order to set the device when a flow of gas is desired to take place through the pipe 11, the pawl 51 is first engaged with the controlling gear 42 and for this purpose the following device may be employed: Through a hole in one side of the box 17 extends a sleeve 85 which is secured to said side in an approved manner as soldering, welding or screwing, and through this sleeve 50 extends a stub shaft 86 which is free to rotate in the sleeve and which is influenced by a spring 87 that urges the prongs 88 and 89, carried by the stub shaft, in a horizontal position as shown in Fig. 3. The angle of rotation of the stub shaft 86 is

determined by a stopper 90 integral therewith which travels in a slot 91 formed in the sleeve 85. This stub shaft 86 may also be provided with a head 92 to afford a finger gripping member. When the head 92 is rotated counter-clockwise, the prongs 88 and 89 are rocked downwardly causing the prong 89 to engage the curved portion of the pole 51 rocking it on its pivot 50 and causing the tooth 53 thereof to engage the teeth 60 of the controlling gear 42. Upon releasing the head 92, the prongs 88 and 89 return to their normal horizontal positions under the influence of the spring 87.

10 The gear mechanism 40 may be set for operation by means of a key 95 which is inserted through an opening 96 in the removable front 18 of the box 17. This key is formed with a socket or slot 97 to engage the head 98 of the shaft 99 of the master gear 41 about which the spring 43 winds. To remove the front 18 of the box 17, which, in the illustrated example, is slid longitudinally of the box for it is held in place by studs 100 secured at both sides of the box 17, the key 95 is first withdrawn. This construction, of course, can be varied as by hinging the front 18 to the box and by making the key 95 a part thereof to eliminate the withdrawal of the key every time the front 18 is removed.

15 When a supply of gas is desired to be drawn for the radiator 10, or like appliances, from the pipe 11, the stub shaft 86 is rotated counter-clockwise through the head member 92 to force the prongs 88 and 89 downwardly and cause the pawl 51 to swing clockwise to engage the tooth 53 thereof with the teeth 60 of the controlling gear 42 and lock the said controlling gear against movement; and to cause the prong 88 to engage with the shank 79 and swing the device 72 to the position as shown in Fig. 3. The master gear 41 is then rotated through the key 95 against the pressure of the spring 43 which gear remains in the charged position while the tooth 53 engage the teeth 60. Then the pilot burner 30 is opened and lit and a few seconds thereafter, the head 92 is released so as to enable the prongs 88 and 89 to return to their normal position, for by this time the radiating air caused by the flame of the burner 30 striking against the floater 73, compels the device 20 72 to remain in the full line position shown in Fig. 3, in which position it stays until the gas supply is either shut off or until any cause may extinguish the flames of the burners.

25 While the floater 73 is in its uppermost position, the mechanism 40 having been turned in the direction in which it opens the valve 21, the valve 21 remains open until there is enough air radiated from the burner 30 to the floater. The moment that, through 30

any unexpected cause, the pressure in the pipe 11 decreases, or that the flame of the burner 30 becomes extinguished the floater 73 not being acted upon by the radiating air as there is no radiating air going toward it, it drops downwardly causing the pawl engager 74 to strike against the concave side of the pawl 51 and move it counter-clockwisely, disengaging the tooth 53 from the teeth 60 and allowing the spring 43 to rotate the master gear 41 and the valve 21 which shuts off the supply of gas to the pipe 11.

Assuming that the pilot burner 30 is not used, the heated air, to keep the floater in its uppermost position, may be supplied by the air radiated in the radiator 10, and the moment that any accident happens, that is, that the pressure of the fluid in the pipe 11 decreases or that any of the burners 14 become extinguished and decrease the amount of radiation within the radiator, the floater 73 will cease to be supported by the radiating air conducted by the conduit 35 and will move downwardly closing the valve 21 in the same manner as if the burner 30 had become extinguished. If desirable, the burner may be used in conjunction with the conduit 35 and the two adjusted so that their combined radiation only will support the floater 73 in its uppermost position. It will also be noted that once the floater 73 begins to move downwardly and the tube 75 passes its horizontal position, the balls 76 will hasten its movement downwardly. The operation of the device is positive and as it will permit the flow of gas only under the circumstances that the gas itself must produce a certain amount of radiating air, the moment that it fails to produce such amount of radiating air, the supply of gas to the appliance or appliances will be shut down completely.

The means described in the illustrated embodiment of course may be changed and varied, as may be found expedient to so do, without departing from the spirit of my invention, which is that of principally controlling the flow of the fluid on thermostatic principles, since fluids employed for illuminating and heating purposes when ignited always create a thermostatic action.

It may also be desired to shut off the gas supply to the gas appliances at a certain pre-determined time without the attendance of the human factor and for this purpose I employ a clock 110 which is detachably mounted on the box 17 by means of any suitable clamping elements such as the plate 11 secured to the case of the clock which co-acts with a stub plate 112 secured to the box 17, and the housings 114 to house the legs 115 of the clock. Any other approved means may be employed for clamping the clock to the box and the ones just described

are only illustrated as an example. Through the top member of the box 17 extends a sleeve 117 held against movement by means of a set screw 118 and accommodating a shaft 120 which shaft carries at both ends tongue members 121 and 122, the tongue member 121 engaging with the key 123 of the alarm winding mechanism of the clock, and the tongue 122 being engageable with the off-set portion 54 of the pawl 51. The lower portion of the sleeve 117 is surrounded by a spring 125, one end of which is secured to the sleeve and the other end bears against the tongue 122 so as to urge the shaft 120 and the tongues 121 and 122 in one direction, that is, in the direction bearing against the off-set portion 54 of the pawl 51 and the key 123 of the clock.

Whenever it is desired to have the gas supply shut off at a certain time, the alarm clock is set to give an alarm at that time, leaving the key 123 bearing against the tongue 121. Upon reaching that time the alarm clock is set off and the key 123 rotating presses against the shaft 120 which turns against the action of the spring 125, causing the tongue 122 to press against the off-set portion 54 and swinging the pawl 51 counter-clockwisely. Thus the tooth 53 is disengaged from the teeth 60 of the controlling gear 42 and the spring 43 is allowed to rotate the gears 40 to close the valve 21 as if the air radiating from the burner was insufficient to support, in the uppermost position, the floater 73.

It is thus seen that through the medium of the mechanism just described, the device forming the subject matter of the invention not only cuts off the fluid supply to the burners whenever those burners fail to support a certain degree of combustion, but also provides the means whereby the fluid supply may be cut off at a specified time, eliminating the human factor, as much as possible, which is now indispensable for taking care of the burners of house appliances.

I would state in conclusion that while the illustrated examples constitute a practical embodiment of the invention, I do not limit myself strictly to the exact details illustrated therein since, manifestly, the same can be considerably varied and changed without departure from the spirit of the invention as is defined in the appended claims.

What I claim as my invention is:

1. An automatic fuel cut-off comprising a fluid pressure actuated means, adjustable means on said fluid pressure actuated means for adjusting the latter for operation at a predetermined fluid pressure, fuel cut-offs means associated with said fluid pressure actuated means for closing the supply of said fuel when the fluid pressure has dropped to or below said predetermined fluid

pressure and a chamber associated with the automatic fuel cut-off through which said moving fluid is made to move in a vertical column out to the atmosphere and in which 5 said fluid pressure actuated means is arranged.

2. An automatic fuel cut-off comprising adjustable means responsive to the change of pressure of a moving fluid escaping to the 10 atmosphere, a valve for shutting off said fuel, valve closing means moved by said adjustable means when the latter is actuated by a change of pressure of the moving fluid and a chamber in which said adjustable 15 means operate and through which said moving fluid is made to move.

3. An automatic fuel cut-off comprising a chamber having a perforated upper wall, an 20 adjustable element adapted to move when the pressure of a fluid passing through said chamber drops to a certain degree and means actuated by said element for stopping the flow of said fuel.

4. An automatic fuel cut-off comprising a 25 valve controlling the flow of the fuel, a chamber through which the heated air and burned gas developed by said fuel pass, an adjustable element adjusted to operate at a certain predetermined pressure of said 30 heated air and gas arranged to operate in said chamber, said element being associated with said valve and closing the same when moving away from its normal position under the change of pressure of the heated air and 35 burned gas.

5. An automatic fuel cut-off comprising an adjustable oscillating device held in a certain adjusted position by the heated fluid developed by said fuel, a valve controlling 40 the flow of said fuel, a mechanism for shutting said valve, means for urging said mechanism in the direction to close said valve, a pawl adapted to be actuated by said oscillating device when the heated fluid developed by the fuel is insufficient to hold 45 said oscillating device in a fixed position, and a chamber in which said oscillating device operates and through which said heated fluid is made to pass out to the atmosphere.

6. An automatic fuel cut-off comprising an adjustable oscillating device held in a certain adjusted position by the heated fluid developed by said fuel, a valve controlling the flow of the fuel, a mechanism to close 50 said valve, urging means for urging said mechanism in one direction, and means for setting said mechanism in a position ready to be urged by said urging means, a pawl to be actuated by said oscillating device when the latter fails to maintain its normal position due to a drop in pressure of the heated fluid generated by the fuel, and a chamber enclosing said oscillating device and through which said heated fluid is made to pass.

7. In an automatic cut-off of the class de-

scribed a box, a valve closing mechanism within said box, a heated fluid chamber, means for supplying heated fluid into said chamber, a floater actuated by the movement of the heated fluid through the chamber, a valve connected with said mechanism, means associated with said mechanism urging said valve into closed position and means normally engaged by said floater to prevent said valve from moving to its closed position.

8. In an automatic cut-off of the class described, a heated fluid chamber, means for supplying a heated fluid into said chamber, the upper side of said chamber being perforated to allow the passage of said heated fluid outwardly, a floater moving below said perforated side and means actuated by said floater for shutting-off the supply of the combustible heating said fluid.

9. An automatic fluid cut-off comprising a valve controlling the flow of the fluid, a chamber through which a portion of the air heated by said fluid when burning may be made to pass in an up and down column, means operated by said heated air arranged in said chamber, and means adapted to be actuated by the heat affected means to close said valve when the pressure of the heated air in said chamber drops below a certain degree.

10. An automatic fluid cut-off comprising a spring actuated valve controlling the flow of the fluid to a burner, a chamber through which air heated by said burner may be made to pass in an up and down column, means responsive to the change of pressure of the air heated by said burner, means detaining said valve in an open position against the action of the spring, and means actuated by said means responsive to the pressure of the heated air to close said valve when the heat developed by said burner or burners drop below a certain degree.

11. In an automatic fluid cut-off of the class described, a valve controlling the flow of the fluid, means for urging the valve to its closed position, means for detaining said valve in the open position, a pressure responsive element engageable with said detaining means to allow the same to permit the valve to move to its closed position when the pressure responsive means move to a certain position due to a change in the heat developed by the fluid, and means carried by the heat responsive means for accelerating the movement of the heat responsive means.

12. In an automatic fuel cut-off controlling the flow of the fluid, means urging said valve to its closed position, a pawl to prevent the movement of said valve under theurgence of said means, fluid pressure actuated means to disengage said pawl when the heat produced by said fuel falls below a certain degree, and means actuated by the

mechanism of a clock to also disengage said pawl at a predetermined time.

13. In an automatic fuel cut-off, a fluid pressure actuated element adapted to cut off the fuel supply to a burner when the burner fails to produce a certain amount of heat, and a mechanism controlled by a clock

to also cut off the fuel supply at a predetermined time, together with manually actuated means for jointly setting in an operative position said fluid pressure means and clock operating mechanism. 10

FRANK COLONNA.
